(57) CLAIM

I claim the ornamental design for a dual-sided, Christmas-tree-with-ornaments cookie cutter, as shown and described.

DESCRIPTION

FIG. 1 is a perspective view of my new design, with the view showing principally front, left side and bottom end exterior surfaces thereof;

FIG. 2 is a front elevational view thereof;

FIG. 3 is a bottom end view thereof;

FIG. 4 is a top end view thereof;

FIG. 5 is a rear elevational view thereof;

FIG. 6 is a left side view thereof; and,

FIG. 7 is a right side view thereof.
